UNITED STATES PATENT OFFICE.

ODIN B. ROBERTS, OF DEDHAM, MASSACHUSETTS, ASSIGNOR TO AUTOMATIC HAMMER COMPANY, OF BOSTON, MASSACHUSETTS, A CORPORATION OF NEW JERSEY.

AUTOMATIC HAMMER.

SPECIFICATION forming part of Letters Patent No. 729,666, dated June 2, 1903.

Application filed June 19, 1901. Serial No. 65,184. (No model.)

To all whom it may concern:

Be it known that I, ODIN B. ROBERTS, a citizen of the United States, and a resident of Dedham, in the county of Norfolk and State of Massachusetts, have invented new and useful Improvements in Automatic Hammers, of which the following is a specification.

My invention relates to automatic tacking tools of which the shoe-lasting hammers described in United States Letters Patent Nos. 620,650, 670,403, 670,496, issued March 7, 1899, March 19, 1901, March 26, 1901, respectively, to Arsene Hebert are types and has to do especially with the mechanism for presenting tacks successively to the acting face of the tack-driver. Tools of this character comprise a tack receptacle or hopper which automatically arranges the tacks in a row on a race-way and tack-separating mechanism which removes the tacks one by one from the row in the raceway and delivers them to the tack-channel, wherein they pass to the tack-driving mechanism. The tack gathering and separating mechanism of the Hebert tools described in the aforesaid patents will serve to assist in illustrating my invention, which I show herein as applied to a tool of this character. The tack gathering and separating mechanism is therefore not shown in detail herein, and I leave it to be understood that suitable tack gathering and separating mechanism, such as that devised by Arsene Hebert, is a part of the organized mechanism of the tool about to be described.

In the drawings hereto annexed, which illustrate an embodiment of my invention, Figure 1 is a vertical longitudinal section of part of a lasting-hammer, showing the working parts of the tack-driving mechanism and devices associated therewith. Fig. 2 is a front view of the hammer-head; Fig. 3, a vertical longitudinal section of the lower end of the hammer-head, showing a modified form of the mechanism for presenting a tack to the driver. Fig. 4 is a detail showing in perspective the tack-check which forms part of the mechanism of Fig. 1, and Fig. 5 is a detail showing the tack-plunger in perspective.

A is the hammer-handle, to which the op-

erative parts of the tool are secured or on 50 which they are mounted.

B represents roughly a tack-separator such as that shown in the Hebert patents aforesaid.

C is the actuating-lever for the tack-separator, and J the detent, controlled by the finger of the person handling the tool.

The parts just mentioned are only indicated herein, as a full description of them and their functions may be found in the Hebert patents.

T is a cylindrical stud which serves as a sliding bearing for the hammer-head, a housing for the spring which normally controls the hammer-head, and as a part of the channel through which tacks descend one by one to the hammer-head as they are separated from the supply-raceway and dropped by the separator substantially as shown in the said Hebert patents.

The stud T, which is screwed or otherwise firmly attached to the handle A, has an inner tube T', between which and the outer shell is a space for the reception of the spring t'. The shell of the stud T is enlarged, so as to 75 form a flange or shoulder t at its lower end. The hammer-head H is for convenience of manufacture made in three divisions, the upper division H' being bored out at h' to receive the stud T. The middle division H² 80 has an outer screw-threaded sleeve h², which screws into a cavity formed for the purpose in the bottom of the division H', and an inner sleeve h³, which serves as a bearing for the spring t', which seats on the top of the sleeve h³, and as a continuation of the tack-channel at T³. The shoulder t on the stud T slides in the space between the inner and outer sleeves h³ and h². The lower section H³ of the hammer-head screws into the bottom of the middle section H² and contains the tack-check, tack-plunger, and tack-stop. The lower end of the tack-channel T³ is inclined from the perpendicular and passes 90 diagonally from the middle section H² through the lower section H³, leading to the tack-receiving chamber and the driver-passage d.

The tack-driver shown in the Hebert pat-

ents is there shown as forming part of the stud or housing, which is here represented at T, and might be so constructed in the tool here described without substantial change in 5 the combinations which embody my invention; but partly for convenience in manufacture and partly to provide for adjustability in effective length of the tack-driver I show the driver here as separate from the 10 stud T and working in its own slide or passage in the hammer-head H.

The driver D is a cylindrical spindle screwed to the handle A at D', provided with a set-nut D² and a polygonal-faced section at 15 D², whereby it may be adjusted with a wrench. The driver - passage d is bored straight through all three sections of the hammer-head H. As the person handling the hammer strikes a blow therewith the hammer-head H slides toward the handle A, compressing the spring t', and the driver D forces a tack previously lodged in the lower end of the driver-passage into the material struck. When the hammer is again lifted, the spring 25 t' pushes the head H to its normal position, as shown in Fig. 1, and the lower end of the driver-passage is ready to receive another tack.

The tack - separating mechanism B is so 30 connected with the movable parts of the tool that it drops a tack into the tack-channel when the spring t' forces the hammer-head to its extended position. The tack falls through the channels T² and T³ and is arrested by the 35 check G.

The check G (seen in detail in Fig. 4) is a 40 reciprocating plunger, forked at its inner end at g', cut away on its lower side at g, and counterbored at g², so that the point of the 45 tack falls between the fork - prongs g' and rests with its head in the counterbore g². The check G is secured at its outer end to the spring G', which is fastened to the block G² on the hammer-head H. This spring G' is cramped, so as to press the check inward 50 constantly. An inclined block G³ is secured to the spring G' and lies in the path of the trip E³, which is hinged at E⁴ to the arm E², which is part of the cam-block E, fast to the 55 handle A at E'. The toe of the trip E³ slides in the groove e, cut in the front of the hammer-head H. Below the check G lies the tack-plunger P, whose head P' slides in the tack-receiving chamber K. This chamber K is open to the lower part of the driver-passage d.

The outer end of the plunger P is jointed 60 to the lever P². This lever is pivoted at P³ in the block G² and has the cam-follower P⁴ secured to its upper end. The cam-groove P⁵, cut in the cam-block E, is so proportioned that as the head H moves up and down the plunger P is reciprocated and its head P' alternately approaches and recedes from the 65 driver-passage d, closing and opening the lower end of the tack-channel in so doing.

A tack is supposed to have fallen on the forked check G. The point of this tack lies in the groove p, cut for the purpose in the plunger-head P', Fig. 5. A blow is struck 70 with the tool, and the head H slides up to the handle A. As it does so, first the plunger-head P' is drawn to the back of the tack-receiving chamber, leaving the tack-channel open at the bottom, except for the check G. Next the trip E² strikes the beveled block G³ and moves the tack-check outwardly, letting the tack drop into the tack-receiving chamber between the face of the plunger-head P' and the side of the driver D, which 80 has descended into the lower part of the driver-passage d. When the trip E³ passes the block G³, the spring G' snaps the check G back into place above the tack, which is thus imprisoned in the tack-receiving chamber K. When the tool is lifted from the work, the spring t' asserts itself, and the hammer-head H is extended. The trip E³ rides over the block G³, being hinged at E⁴, and its spring E⁵ returns it to place for the next 85 stroke. The driver D ascends in the hammer-head and the cam P⁵ causes the plunger-head P' to move toward the driver-passage d, pushing the tack into the driver-passage and "closing the door" (so to speak) behind it. 90 The spring-stop S, pivoted in the slot h⁵ at s', forked at s and under the control of the spring s', keeps the tack in the driver-passage until the next descent of the driver forces the stop S to one side and the tack into the work. 95 Meanwhile another tack has dropped on the check G and the tool is ready for another excursion.

The check G is employed for the sake of extra precaution against a tack jumping back 105 out of the receiving-chamber K; but with intelligent handling the tool will work accurately without the check G. In such case the lower end of the hammer-head may be constructed as shown in Fig. 3, where the plunger-head P lies directly across the lower end of the tack-channel T³.

The groove p in the plunger-head in this construction is proportioned so that a tack lies with its head resting on the top of the 115 plunger-head and its point in the notch. The functions of the plunger are the same as in the construction described at length above.

If it is desired to drive tacks only part way, so that they may be extracted from the work 120 easily, the driver D is lowered farther into the socket at D' and the set-nut D² secures it in place. The top section H' of the hammer-head is counterbored at d' to admit the set-nut D². When the three parts of the head H 125 are screwed together, binding-screws h⁴, Fig. 1, and m, Fig. 2, serve to lock them in place.

What I claim, and desire to secure by Letters Patent, is—

1. In a tool of the character described, the 130 combination of a handle, a hammer-head slid- 135 ily mounted thereon, a tack-driver, a pas-

sage therefor in the hammer-head, a tack-receiving chamber beside the lower end of the driver-passage and open thereto, a tack-channel leading to the tack-receiving chamber, a plunger in the receiving-chamber, movable therein toward and from the driver-passage, and plunger-actuating mechanism connected to the plunger, whereby it is reciprocated in the tack-receiving chamber across the end of the tack-channel at each excursion of the hammer-head.

2. In a tool of the character described, the combination of a handle, a hammer-head slidingly mounted thereon, a tack-driver, stationary with relation to the handle, a driver-passage in the hammer-head, a tack-receiving chamber in the hammer-head beside the lower end of the driver-passage, and open thereto, a tack-channel leading to the receiving-chamber, a plunger in the receiving-chamber movable toward and from the driver-passage and mechanism connected with the plunger whereby, when the hammer-head slides away from the handle, the plunger is moved toward the driver-passage and across the tack-channel, and vice versa when the hammer-head slides toward the handle.

3. In a tool of the character described the combination of a handle, a hammer-head slidingly mounted thereon, a tack-driver, a passage therefor in the hammer-head, a tack-receiving chamber beside the lower end of the driver-passage and open thereto, a tack-channel leading to the tack-receiving chamber, a plunger reciprocally movable therein

toward and from the driver-passage, a tack-check lying across the tack-passage above the plunger, and actuating mechanism for the plunger and tack-check, whereby they are vibrated across the end of the tack-channel at each excursion of the hammer, substantially as described.

4. In a tool of the character described, the combination of a handle, a hammer-head slidingly mounted thereon, a tack-driver, its passage in the hammer-head, a tack-receiving chamber, a tack-channel, a plunger, its operating-lever and cam, a tack-check, its spring, a tack-check trip, a projection on the check-spring actuated by the trip, and a spring-controlled tack-stop in the lower end of the driver-passage, substantially as described.

5. In a tool of the character described, the combination of a handle, a hammer-head slidingly mounted thereon, a tack-driver, its passage in the hammer-head, a tack-receiving chamber, a tack-channel, a plunger, its operating-lever and cam, a tack-check, its spring, a hinged tack-check trip, a projection on the check-spring actuated by the trip, and a spring-controlled tack-stop in the lower end of the driver-passage, substantially as described.

Signed by me at Boston, Massachusetts, this 13th day of June, 1901.

ODIN B. ROBERTS.
